Attorney

UNITED STATES PATENT OFFICE.

ELIJAH RHODES, OF HUNTINGTON, WEST VIRGINIA.

DRENCHING-BOTTLE.

1,383,426.

Specification of Letters Patent.

Patented July 5, 1921.

Application filed September 24, 1919. Serial No. 325,986.

To all whom it may concern:

Be it known that I, ELIJAH RHODES, a subject of the King of England, residing at Huntington, in the county of Cabell and 5 State of West Virginia, have invented certain new and useful Improvements in Drenching-Bottles, of which the following is a specification, reference being had to the accompanying drawings.

10 This invention relates to certain improvements in drenching bottles, and has relation more particularly to a device of this general character especially designed and adapted for use in connection with horses, cattle and 15 other stock, and it is an object of the invention to provide a novel and improved device of this general character which can be readily and conveniently manipulated, and which can be employed with convenience and facility in accomplishing the purpose intended.

It is also an object of the invention to provide a novel and improved device of this general character provided with a discharge 25 nozzle constructed in a manner to assure the desired egress therethrough.

The invention consists in the details of construction and in the combination and arrangement of the several parts of my improved 30 drenching bottle whereby certain important advantages are attained and the device rendered simpler, less expensive and otherwise more convenient and advantageous for use, as will be hereinafter more fully 35 set forth.

The novel features of my invention will hereinafter be definitely claimed.

In order that my invention may be the better understood, I will now proceed to 40 describe the same with reference to the accompanying drawings, wherein—

Figure 1 is a view partly in side elevation and partly in section, illustrating a drenching bottle constructed in accordance 45 with an embodiment of my invention;

Fig. 2 is a view in elevation of the discharging end of the nozzle, as herein embodied, and,

Fig. 3 is a view in top plan of the nozzle 50 and coacting reducing coupling, as herein included.

As disclosed in the accompanying drawings, my improved drenching bottle comprises an elongated tubular member M 55 curved longitudinally on a desired radius.

An end of the member M is tightly sealed

or closed by a plug P, preferably of hard wood, driven within said end portion of the member M. The outer end portion of the plug P is continued to form a handle or hand grasp H, whereby the device in its entirety may be conveniently and effectively manipulated, and particularly during the period when a dose is being administered to an animal. The outer extremity of the hand grasp 65 or handle H is provided with an eye member E or the like to afford means whereby the device can be readily suspended from a nail or other supporting member when not in use.

The opposite end portion of the member 70 M is provided with the external threads I, with which engages a reducing coupling R, and threaded or otherwise detachably engaged within the outer or reduced portion of the coupling C is a nozzle N. The nozzle 75 N has its outer end portion gradually reduced and in a manner whereby the discharge opening thereof is substantially elliptical in form with its major axis preferably substantially at right angles to the radius 80 of the member M.

The nozzle N can be removed or applied with convenience and facility whereby the member M can have readily applied therein the liquid, medicated or otherwise, with 85 which it is desired to dose an animal. The particular formation of the nozzle N materially facilitates the dosing of the animal while the configuration of the member M and the particular location of the hand 90 grasp or handle H materially facilitates the desired manipulation of the bottle.

The parts of my improved bottle, with the exception of the hand grasp or handle H, are preferably formed of metal, and it is to be 95 particularly noted that in its structure my improved device comprises but four parts, which may be readily assembled, and which can also be easily replaced if the necessities of practice should so require.

It will also be obvious that my improved device when assembled, is substantially rigid, and which in itself, is of extreme importance during the use of the bottle.

100 From the foregoing description, it is though to be obvious that a drenching bottle constructed in accordance with my invention is particularly well adapted for use by reason of the convenience and facility 110 with which it may be assembled and operated, and it will also be obvious that my

invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

10 As an article of manufacture, a drenching bottle comprising an arcuate tubular member, the diameter of said member being the same at any point longitudinally there-

of, whereby the contents of said member may pass unrestrictedly therethrough, a coupling 15 threaded on one end of said tubular member, a nozzle carried by said coupling, said nozzle being slightly smaller than the tubular member, and a plug for closing the other end of the tubular member, said plug being 20 in continuity with said arcuate tubular member.

In testimony whereof I hereunto affix my signature.

ELIJAH RHODES.
